UNITED STATES PATENT OFFICE.

HUDSON MAXIM, OF HOPATCONG, NEW JERSEY.

GAME OF SKILL.

1,030,521.

Specification of Letters Patent. Patented June 25, 1912.

Application filed November 24, 1909. Serial No. 529,767.

To all whom it may concern:

Be it known that I, HUDSON MAXIM, of the borough of Hopatcong, county of Sussex, State of New Jersey, have invented a new 5 and useful Improvement in Games of Skill, which invention is fully set forth in the following specification.

The present invention relates to improvements in games of skill of that class to which 10 chess and checkers belong, wherein pieces representing men or insignia of powers or positions are employed and given certain moves upon a checkered board or a board laid out in a given number of checks, squares 15 or rectangles, alternating in color with one another.

One object of the invention is to provide a game which shall simulate or symbolize war, or military operations and tactics, especially 20 land operations in battle or in seige.

In carrying out the invention, I employ a board having one hundred squares or rectangles; and in addition to the one hundred squares, four additional spaces, preferably 25 circular, are used as perches or stations for pieces representing flying machines.

The pieces employed in the game may be of any desired shape or form, and as here shown are designed to represent and, to some 30 extent to symbolize, the parts played in actual war by the persons and things they symbolize.

For the purpose of describing the invention and indicating one manner of playing 35 the game and providing certain given powers and moves for the several pieces, I will describe the pieces when having their preferred form symbolizing the parts played in war by the persons and things they represent, and will indicate certain powers and moves which may be assigned to such pieces. It will be understood, however, that the 40 pieces may have other forms than those herein described for purposes of illustration, and may have other moves and powers of capture, etc., than those herein specifically described, without departing from the spirit of the invention. For example, all of the pieces shown as occupying the rear lines in 45 Figure 10 may have the form of the principal pieces in chess, and the pieces shown as occupying the third and fourth lines from the rear in said Fig. 10 may have the form of the pawns in chess, and all of these various 50 pieces may have assigned to them by

arbitrary rules such moves and capturing powers as may be deemed desirable. Likewise, the flying machine pieces illustrated in Fig. 7, and also in the circular stations exterior to the checkered surface in Fig. 10, 55 may be given any desired form, and have any desired power assigned to them, though I prefer, as hereinafter described, to give these pieces a form designed to symbolize a flying machine, and to assign to such pieces the power of blocking any given square on the checkered surface, in order that such pieces may by their powers symbolize the blowing up or destruction of bridges or the 60 breaking of lines of communication. 70

While the pieces may have any preferred forms and powers of movement, I prefer to give them the forms illustrated in the accompanying drawings, and to assign to them the names and the moves and powers of capture hereinafter described. 75

The king, president or other head of the government, is represented by an arbitrary symbol, being a pedestal of regular contour upon which rests a crown, the pedestal being 80 preferably decorated with crossed swords or other insignia of war. This piece representing the king or president has the same moves as does the king in chess—that is to say, it is capable of moving in any direction one square at a time, and also has the power of taking any piece of an opponent which may be opposed to it on an immediately adjacent square. This piece representing the king or president is set upon a specially marked 85 square or space intended to symbolize a citadel. The king or president, and the general or commanding officer, stand side by side, as the king and queen in chess, the general occupying a position at the right of the king on one side of the board (the red side), and at the left of the king on the opposite side of the board (the blue side), corresponding 90 with the positions of the king and queen in chess. 95

The general is represented by a piece consisting of an eagle perched upon a round ball, mounted upon a pedestal; and this piece has the same movements as the queen in chess, being able to pass in any direction 100 across the board, and to any distance, when unopposed by other pieces, and having the power to take any piece of an opponent in any direction. 105

The siege artillery is represented or sym- 110

bolized by a piece representing an old-style mortar, mounted on a base and with a round projectile in the muzzle. This piece is given the same moves as those of the castle in chess—that is to say, the piece has the power of moving straight forward and backward or at right angles, and to any distance across the board when unimpeded by other pieces, and has the power of taking the pieces of an opponent in the same manner as does the castle in chess; and this piece occupies the end squares at right and left in the first line of squares upon the board, as in chess.

The cavalry, or horse, is represented by a piece of the same general appearance and character as that known as the knight in chess, namely, the emblem of a horse's head mounted upon a base; and the horse in the present game has the same movements and the same power to take pieces of the opponent as does the knight in chess—that is to say, its movements are one square diagonally and one square straight. This piece is initially placed upon the second square from each end, corresponding with the square occupied by the knight in chess.

The field artillery, or cannon, is represented in the present game by a piece symbolizing an old-style, muzzle-loading field-guns, mounted upon a suitable base. This piece has the same movements as the bishop in chess, being able to pass in any direction diagonally across the board to any distance and to take any piece of an opponent which may be opposed to it in its line of passage. There are also ten pieces on each side employed to represent or symbolize lines of troops, positioned on alternate squares upon the third and fourth lines of checks from each side of the board next to the players, five in number on each line, the pieces being placed upon the black squares on the red side, and the white squares on the blue side of the board. These pieces have in the main the combined movements of those of chess and checkers, as hereinafter described. For contrast, I employ black and white as the alternating colors of the squares of the board, and blue and red as the distinguishing colors of the opposing pieces; which are referred to as the blue and red respectively. The next adjacent squares at the right and left of those occupied by the king and commanding officer, or general, are unoccupied at the beginning of the game; and immediately back of these vacant places are circular spaces which serve as the perches or stations of the pieces representing flying machines. These perches are of different colors, the color of each corresponding to that of the square adjacent to it, one being black and one white.

The flying machines are symbolized by small pieces, consisting of a circular base, and an upward-projecting, conical shaft,

terminating at the top in a ball, upon which shaft are flanges representing the aeroplanes of a flying machine. These flying-machine pieces have the power of moving or flying from their perches over intervening pieces to any unoccupied square upon the board whose color corresponds with that of the perch upon which they normally rest. The flying machines are each able to make but one move during the game, and are employed to block the movement of a piece of an enemy, and when placed upon a square, no other piece of either contestant is afterward able to move upon or to pass over that square during the game, the idea being to symbolize the blowing-up of bridges or the destruction of other means of communication from point to point. The other pieces already mentioned are arranged upon the rear line of each side in a similar manner to that of the pieces in chess whose movements correspond with theirs. Beginning with the king upon the citadel, the general occupies the next square at the right upon the red side, and the next square at the left upon the blue side; and then upon each side of the king and general upon both sides of the board are unoccupied squares, and immediately behind these unoccupied squares are four circular spaces or areas, one black and one white on each side of the board, upon which pieces are placed symbolizing the flying machines. Next on each side, in regular order come the pieces symbolizing the field artillery or cannon, then the pieces symbolizing the horse or cavalry, and lastly, upon the corner squares are placed the pieces symbolizing mortars or siege artillery.

Referring to the accompanying drawings: Fig. 1 represents the checkered board on which the game is played. Fig. 2 represents the king or chief civil officer, of which there is one on each side. Fig. 3 represents the general or commanding officer, of which there is one on each side. Fig. 4 represents the cavalry or horse, of which there are two on each side. Fig. 5 represents the cannon or field artillery, of which there are two on each side. Fig. 6 represents the mortars or siege artillery, of which there are two on each side. Fig. 7 represents the flying machines, of which there are two on each side. Fig. 8 represents the larger or rear troops, of which there are five on each side. Fig. 9 represents the smaller or van troops, of which there are five on each side. Fig. 10 shows the location of the respective pieces upon the board, each being in its proper position at the beginning of the game.

In Fig. 1, 1 indicates the black checks or squares and 2 the white checks or squares; 3 represents the red citadel, which is a battlemented area in one of the black squares, colored red, upon which the red king is placed; 4 represents the blue citadel, which

is a battlemented area in one of the white squares, colored blue, upon which the blue king is placed; on the corner squares 5 are placed the mortars or pieces representing the siege artillery; on squares 6 are placed the horse or pieces representing the cavalry; on squares 7 are placed the cannon or pieces representing the field artillery; squares 8 are unoccupied at the beginning of the game; on squares 9 are placed the generals or commanding officers. Circles 10, of which there are two on each side, one black and one white, are the perches or stations for the pieces symbolizing the flying machines. Circular spaces 11 in the black squares on the red side are colored red, and mark the positions, at the beginning of the game, of the red pieces representing the troops on the red side, the larger pieces being placed on the rear line and the smaller pieces on the front line. Circular spaces 12 in the white squares on the blue side are colored blue, and mark the positions at the beginning of the game, of the blue pieces representing the troops on the blue side, the larger pieces being placed on the rear line, and the smaller pieces on the front line. There are, therefore, forty pieces in all, twenty red and twenty blue.

The game is played by two players, with the board between them, the red side next one player and the blue side next the other player. The choice of colors and the first move may be determined either by lot or agreement. The game is opened by one player moving any piece, according to the rules of movement in the game hereinafter described, each player taking turns with alternate moves until the end of the game, which is brought about, and the game won, by one of the players advancing a piece into the citadel of his adversary and maintaining it there without capture for one move.

The moves of the pieces are as follows:

The king moves one square in any direction, straight or diagonally, right or left, forward or back, as does the king in chess. The general moves any number of squares in any direction, straight or diagonally, right or left, forward or back, as does the queen in chess. The cannon move any number of squares diagonally upon their own color, but must always keep to their color, the same as the bishops in chess. The horse or cavalry move one square diagonally and one straight, as do the knights in chess. The mortars or siege artillery move straight any number of squares, right or left, forward or back, the same as do the castles in chess.

The troops have the combined movements of the pieces in checkers or draughts and the pawns in chess; that is to say, they move in any forward direction, straight or diagonally; and when moving straight forward at the first move, they may move two

squares; after the first move, only one square at a time; but when moving diagonally they are able to move but one square at a time. They can never move backward or sidewise. Each flying machine has only a single move 70 in a game, which is over any intervening pieces and upon any unoccupied square whatsoever of the color of its station, except the two citadels, after which move it must remain where placed until the end of 75 the game, thus blocking the square against any other piece of either color occupying it or passing over it. No piece can be moved to a square occupied by another of its own color. No piece can pass over a square occupied by a piece of either color, except the cavalry and the flying machines, which are able to leap over any intervening piece or pieces to an unoccupied square, and the troops in making their jumping moves to 80 take pieces, as in checkers. The flying machines alone, of all the pieces, can neither capture nor be captured. The captured pieces are removed from the board. A troop can capture only a piece on an adjacent square diagonally in front of it, either by occupying the square of the piece thus captured as in chess, or, when the piece opposing is a troop, but not otherwise, by leaping over it to the next adjacent square 85 beyond the captured piece diagonally as in checkers, provided that the square beyond, of course, be an unoccupied square at the time; and if the troop elects to jump, then should there be two or more troops in position 90 checkers, it must either take by so jumping, or, as in checkers, take all of the troops of his opponent thus offered. Although a troop can move forward upon an unoccupied square lying before it in a straight line, it cannot capture a piece on such square, nor can an opponent take a piece *en passant* as in chess. When one or more troops are offered to a troop of the opposing color, to be taken by jumping as in 95 checkers, it must either take by so jumping, or, if the taking player shall elect, the capture may be made by moving upon the square of the offered troop to capture it, or the capture of the offered troop may be 100 made instead by any other piece bearing upon the square at the time. When a player offers a troop to be jumped or taken by a troop of an opponent, if the taking troop be also in a position to take a larger 105 or more important piece, it is at the option of the player which piece he shall take. Any troop having reached the last rank on the far side of the board cannot then be captured, but remains dead on the square for 110 the remainder of the game, and such square is henceforth blocked by the dead troop against occupancy or passage over it by any piece of either color. This rule, however, does not apply in the case of a troop's en- 115

120

125

130

trance into the citadel of the opposite side, when it is liable to be captured by the enemy, but has itself no further move.

The forms of pieces, moves assigned there-
5 to, powers of capture and other rules for
playing the game hereinbefore described,
are those which I prefer to employ, and are
herein set forth for the purpose of enabling
the invention and one manner of using the
10 same to be fully understood. But as before
mentioned, the invention (which consists
of the checkered board, of the peculiar con-
struction shown and described, and with
suitable pieces arranged thereon at the be-
15 ginning of the game, as shown in Fig. 10
and described in the specification, and de-
fined in the claims) is not limited to such
forms, powers of movement and capture,
and rules, since other forms of pieces, with
20 different powers assigned thereto, or dif-
ferent rules for playing the game, may be
laid down if desired, without departing
from the spirit of the invention.

The invention which I desire to claim is
25 as follows:—

1. A game apparatus comprising a checkered board divided into one hundred squares, arranged in transverse rows of ten squares each and having the squares of two
30 contrasting colors alternating with each other, and two stations exterior to the checkered surface of the board on one side thereof one being colored to correspond with one set of squares and the other to correspond with the other set of squares, two stations of like
35 positions and colors on the opposite side of the board, and two sets of pieces, the two sets being of contrasting colors and each set being arranged with some of its pieces in the squares of the checkered surface and some of its pieces on the stations exterior to said checkered surface.

2. A game apparatus comprising a checkered board divided into one hundred squares
45 arranged in transverse rows of ten squares each, and having the squares of two contrasting colors alternating with each other, and two stations exterior to the checkered surface of the board on one side thereof one being colored to correspond with one set of squares and the other to correspond with the other set of squares, two stations of like
50 positions and colors on the opposite side of the board, and two sets of pieces, the two sets being of contrasting colors and each set being arranged with two of its pieces on said stations, eight of its pieces on the rear or first row of squares and ten of its pieces on the third and fourth rows of squares of

its side of the board, the second or next to 60 rear row being left vacant.

3. A game apparatus comprising a checkered board divided into one hundred squares arranged in transverse rows of ten squares each, and having the squares of two contrasting colors alternating with each other, and two stations exterior to the checkered surface of the board on one side thereof one being colored to correspond with one set of squares and the other to correspond with the other set of squares, two stations of like positions and colors on the opposite side of the board, and two sets of pieces, the two sets being of contrasting colors and each set being arranged with two of its pieces on 70 said stations, eight of its pieces on the rear or first row of squares and ten of its pieces on the third and fourth rows of squares of its side of the board, the second or next to rear row being left vacant, and the pieces on 75 the third and fourth rows all being arranged on squares of the same color.

4. A game apparatus comprising a checkered board divided into squares arranged in right lines or rows with the alternating 85 squares of two contrasting colors, and four perches or stations arranged outside the checkered surface two on each of two opposite sides of the board, said stations being arranged adjacent to squares in the first 90 or rear rows of the opposing sides and each station being colored to correspond to the color of the square immediately in front of it in said first or rear row.

5. A game apparatus comprising a checkered board divided into one hundred squares, arranged in transverse rows of ten squares each and having the squares of two contrasting colors alternating with each other and four stations of contrasting colors 100 associated with the two outside transverse rows of squares, said two outside rows each having a square characterized as a citadel, the third and fourth rows on each side of the board having their alternate squares 105 characterized as troop stations and pieces equal in number to the last-named stations, and other pieces equal in number to said outside stations and other pieces four less than the squares in the front and rear rows 110 of squares.

In testimony whereof I have signed this specification in the presence of two subscribing witnesses.
